Primary Examiner—Doris V. Coles

[57] CLAIM

The ornamental design for a tool for untangling backlashed fishing line, as shown and described.

DESCRIPTION

FIG. 1 is a perspective view of the tool for untangling backlashed fishing line showing our new design;

FIG. 2 is a front elevational view thereof;

FIG. 3 is a rear elevational view thereof;

FIG. 4 is a right end elevational view thereof, the left side elevational view being a mirror image of the view shown in this Figure;

FIG. 5 is a top plan view thereof; and,

FIG. 6 is a bottom plan view thereof.
